F. A. BROWN

KEY HOLDER

Filed Aug. 24, 1922

Technical drawing of a wooden frame structure labeled 'Fig. 4. 4'. The drawing shows a rectangular frame with various components labeled with numbers: 1, 2, 3, 4, 5, 6, 7, 8, 9, 10, and 11. The frame appears to be made of wood, with some parts being horizontal and others vertical. The labels are distributed across the different parts of the structure.

UNITED STATES PATENT OFFICE.

FRANK A. BROWN, OF KANSAS CITY, MISSOURI.

KEY HOLDER.

Application filed August 24, 1922. Serial No. 204,618.

To all whom it may concern:

Be it known that I, FRANK A. BROWN, a citizen of the United States, residing at Kansas City, in the county of Jackson and 5 State of Missouri, have invented certain new and useful Improvements in Key Holders; and I do hereby declare the following to be a full, clear, and exact description of the invention, such as will enable others skilled 10 in the art to which it appertains to make and use the same.

The invention relates to a holder for keys which may be carried in the pocket without causing excessive wear thereto and to the 15 garment, and which will enable the desired key to be readily selected when required to open a lock and which enables the ready identification in the case of loss, since provision is had for receiving a card containing 20 the name, address and other desired matter.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the application,

Figure 1 is a perspective view of a key holder embodying the invention as it appears when closed for convenience of carrying in the pocket,

Figure 2 is a front view, the cover being extended,

Figure 3 is a sectional detail of a portion 40 of the cover, the key plate attached thereto, and the identifying card, and

Figure 4 is a detail perspective view of the key plate.

Corresponding and like parts are referred 45 to in the following description and designated in the several views of the drawings by like reference characters.

The holder comprising a cover 1 which may be of any suitable material, such as 50 leather or textile which is flexible, yet sufficiently rigid to maintain a predetermined

shape and admit of portions folding. A separable fastening 2 secures the cover when folded, the complementary parts being applied to opposite edge portions thereof. A 55 key plate 3 is attached to the inner side of the cover adjacent an edge thereof and is provided along its outer edge with an inwardly disposed flange 4 in which is formed a plurality of openings 5 for the attachment 60 thereto of a plurality of short chains 6 or like connections having snap hooks 7 connected thereto by means of a swivel joint, whereby the keys 8 may be turned without twisting the chains or connections 6. An 65 opening 9 is formed in the plate 3 and exposes a card 10 which is disposed between the plate 3 and cover 1 and upon which the name and address of the owner appear for identification. A transparent plate 11 extends over the opening 9 and protects the card 10 and is preferably secured to the cover 1 by the same means employed for attaching the plate 3 thereto. Eyelets 12, or other suitable fastening means, may be employed for attaching the plate 3 to the cover 70 1. The cover 1 is oblong and the key plate 3 is disposed intermediate the ends thereof so that end portions of the cover may fold upon the plate 3 and keys 8 and enclose the 75 same, as indicated most clearly in Figure 1, whereby to form a neat packet for carrying in the pocket and which will protect the same from injury such as results from carrying keys in the pocket without any covering applied thereto. When the cover 1 is extended, as indicated in Figure 2, the keys 8 are spread so that the desired key may be 80 readily selected. The snap hooks 7 enable the keys to be readily applied to or easily detached from the holder, and by reason of the 85 swivel connection between the snap hook and the connection 6, the key may be turned without twisting the connection.

What is claimed is:

A key holder comprising a flexible cover, a rigid key plate attached to the inner side of the cover adjacent an edge thereof and intermediate the ends of the cover to admit of end portions of the cover folding thereover, said plate having an inwardly disposed flange along its outer edge and having 90 100

an opening for exposing an identification card disposed between the plate and cover, and key attaching means connected to said inwardly disposed flange, said key attaching means consisting of short chains having snap hooks connected to their free ends by means of swivel joints.

In testimony whereof I affix my signature in presence of two witnesses.

FRANK A. BROWN.

Witnesses:

EARL E. BARKER,
Mrs. M. D. CAMPBELL.
